ATTORNEY.

UNITED STATES PATENT OFFICE.

FRED R. TAISEY, OF INDIANAPOLIS, INDIANA.

TROLLEY.

SPECIFICATION forming part of Letters Patent No. 678,143, dated July 9, 1901.

Application filed September 8, 1900. Serial No. 29,432. (No model.)

To all whom it may concern:

Be it known that I, FRED R. TAISEY, of Indianapolis, county of Marion, and State of Indiana, have invented a certain new and useful Trolley; and I do hereby declare that the following is a full, clear, and exact description thereof, reference being had to the accompanying drawings, in which like numerals refer to like parts.

10 The chief feature of the invention consists in pivoting a trolley-carrying arm and a guarding fork or lever on a suitable support, so that they will be vertically movable, and connecting them, so that the vertical movement of one will cause the vertical movement of the other at a different speed. The object of this feature of the invention is to prevent the trolley from escaping from the wire. The instant the trolley starts to leave the wire the 15 guarding-fork moves upward much more rapidly. This feature of the invention is carried out here more specifically by pivoting the trolley-carrying arm away from its end and providing a spring which tends to elevate the 20 trolley end and depress the other end of the arm. The guarding-fork is pivoted to the same support much nearer its end than the arm, and a link-bar connects the ends of the arm and guarding-fork, so that any downward 25 movement of the inner end of the arm would cause the elevation of the guarding-fork more rapidly than the trolley. As here shown, the guarding-fork would move upward three times as fast, so that the trolley could not make 30 any appreciable movement upward away from the wire until the fork would be elevated above the wire, thus preventing the escape of the trolley.

The full nature of my invention will be understood from the accompanying drawings and the description following of one form of device embodying said invention, and the scope of said invention will be understood 40 from the claims following said description.

45 In the drawings, Figure 1 is a side elevation of the device with the parts in section, as shown, and the trolley-pole partly broken away. Fig. 2 is a plan of the same, parts being in horizontal section, as shown, and the 50 trolley-pole shown in dotted lines to one side. Fig. 3 is a side elevation of a portion of the device, showing the guarding-fork elevated.

In detail, 1 represents the conducting-wire, and 2 the trolley-pole, which, as is understood by all, is usually connected with the top of 55 an electric car and extends upward at an inclination rearward. Enlargement of the upper end of the trolley-pole is effected by securing the casting 3 to the pole. It is horizontally recessed at 4 to receive the extension 60 5 of the support or frame 6. The pivot-pin 7, which is held stationary by the screw 20, extends vertically through a suitable hole in said extension 5 and the portions of the casting 3 that lie above and below the extension 65 5 and the support 6. In other words, the mounting of the support 6 is such as to render it horizontally movable or oscillatory. It is held normally in alinement with the pole by the flat spring 8, that rests against 70 the pivot-pin 7 at a point where said pin is flattened on two opposite sides, as appears in Fig. 1 and by dotted lines in Fig. 2, to form recesses 22 in said pin. The spring is provided with two parallel arms which bear 75 against the flat sides of the recessed portion of the pivot-pin and extend through an opening made at 9 in the extension 5 of the support and bear laterally against the inner surfaces of the two sides of the support 6, as appears in Fig. 2. Said spring is held in horizontal position by the opening 9, through which it extends. It is apparent from this that the support 6 can be swung laterally somewhat and will normally be returned to 80 a position in alinement with the pole by said spring 8.

The trolley-carrying arm 10 is pivoted to the support 6 by the pin 11 at a point away from its end. A spring-wire 12 is coiled about 90 the hub 13 on the trolley-carrying arm. One end (the left-hand end as appears in the drawings) of said wire is turned outward and enters horizontal holes at 21 in the two sides of the support 6. The other end is looped across 95 the inner end of the trolley-carrying arm 10, as appears in Figs. 1 and 2. The tendency of this spring is to throw the outer end of the trolley-carrying arm upward and the inner end downward. The outer end of said arm 100 will be usually held down by the wire 1, it acting on the trolley 14, that is pivoted between the two branches 15 of said arm.

The guarding-fork 16 is pivoted to the sup-

port 6 by the pin 17 at a point nearer its end than the pivot-pin 11 is to the end of the arm 10. As here shown, the distance between the end of the arm 10 and its pivot-pin is about 5 three times greater than the distance between the end of guarding-fork 16 and its pin 17. A link-bar 18 pivotally connects the ends of said arm 10 and guarding-fork 16. Said guarding-fork is curved downwardly some- 10 what for a portion of its length and then turned upward and bifurcated, with one prong of the fork extending on each side of the trolley, but both extending between the branches 15 of the trolley-carrying arm 10, 15 as appears in Fig. 2. The outer end of said fork turns downward over the end of the arm carrying the trolley and rests normally on the end of said arm. The prongs or branches of said guarding-fork are widened on their up- 20 per sides at the upward curve about the end of the trolley-support at 19, as shown in Fig. 2, to furnish additional means for preventing the escape of the trolley by mere lateral movement thereof.

25 From the foregoing description it is seen that the action of this trolley-guard is automatic. If the trolley escapes from the wire and starts upward, the end of the guarding-fork will swing upward at three times the 30 speed of the trolley. In fact, by the time the trolley-pole is depressed enough to let the side flanges of the trolley escape from the wire the guarding-fork is elevated above the wire. Trolleys usually escape by the downward 35 movement of the upper end of the trolley-pole, and such downward movement of the upper end of the trolley-pole has the same effect by way of elevating the guarding-fork as the upward movement of the trolley, as it 40 lowers the inner end of the trolley-carrying arm, and any movement of either trolley or pole which will lower the inner end of the trolley-carrying arm will throw the guarding-fork upward at about three times the speed 45 of the trolley or the upper end of the trolley-pole. The upward position of the guarding-fork is illustrated by Fig. 3.

What I claim as my invention, and desire to secure by Letters Patent, is—

50 1. The combination with a trolley-pole, of a vertically-movable trolley-carrying arm, a vertically-movable guarding-fork, means for supporting them, and a connection between said arm and guarding-fork whereby one

while vertically moving will vertically move 55 the other at a different speed.

2. The combination with a trolley-pole, of a support, a trolley-carrying arm and guarding-fork both fulcrumed to said support away from their ends, the fulcrum of said guarding-fork being farther from its end than the fulcrum of the arm, means for moving one of said members vertically, and a bar pivotally connecting the ends thereof. 60

3. The combination with a trolley-pole, of a support, a trolley-carrying arm fulcrumed to said support away from its end, said arm having a hub at its fulcrum, a spring coiled about said hub with one end secured in the 70 support and the other end of the spring acting on the arm to elevate the outer end thereof, a guarding-fork with its prongs normally resting on each side of the trolley, said fork being fulcrumed to said support at a point 75 nearer its end than the fulcrum of said arm is to the end of the arm, and a bar pivotally connecting the ends of said arm and guarding-fork. 65

4. The combination with a trolley-pole, of a casting secured to the upper end thereof with its end horizontally recessed, a vertical pivot-pin mounted in said casting and extending through said recess, said pin having at one point oppositely-flattened sides, a trolley-carrying arm, a support, two vertical sides between which said trolley-arm is secured, and a flat spring that surrounds the flattened portion of the pivot-pin with its free ends pressing against the sides of said support. 80

5. The combination with a trolley-pole, of a horizontally-movable casting or extension pivoted thereto, a vertically-movable trolley-carrying arm mounted on said casting or extension, a vertically-movable guarding-fork 95 also mounted on said casting or extension, and a connection between said trolley-carrying arm and guarding-fork whereby one while vertically moving will freely move the other at a different speed. 90

In witness whereof I have hereunto affixed my signature in the presence of the witnesses herein named.

FRED R. TAISEY.
